UNITED STATES PATENT OFFICE.

JAMES JACKSON, OF MANSFIELD, OHIO.

BANANA-SHIPPING CASE.

SPECIFICATION forming part of Letters Patent No. 655,625, dated August 7, 1900.

Application filed March 3, 1900. Serial No. 7,160. (No model.)

To all whom it may concern.

Be it known that I, JAMES JACKSON, a citizen of the United States, residing at Mansfield, in the county of Richland and State of Ohio, 5 have invented certain new and useful Improvements in Banana-Shipping Cases, of which the following is a specification.

My invention relates to improvements in banana-cases; and the objects of my invention are, first, to provide a case in which can be shipped bananas without packing; second, to so construct the case that when a bunch of bananas are placed within the same it will be impossible to bruise them in any way, 15 and, third, to so construct and arrange the case that when the bananas are placed within the same they will be suspended upon springs either in a vertical or horizontal position. These objects I accomplish by the 20 mechanism illustrated in the accompanying drawings, in which—

Figure 1 is a view showing the general construction, a portion of the mouth of the sack removed, showing a bunch of bananas packed 25 for shipping. Fig. 2 is a vertical sectional view of same to show more fully the construction and arrangement of the parts constituting the packing-case.

Letters of reference indicate the several 30 parts throughout the views.

In the accompanying drawings, A indicates a circular skeleton frame composed of six vertical strips B. The said strips of wood are secured to the wire hoops C by any suitable 35 mechanism. The lower hoop D, I have shown as made of wood, but metal can be used.

E indicates an inner frame composed of six vertical strips of wood G, arranged in line with the strips B and connected to them by 40 bed-springs F, one near the top and one near

the bottom of each strip. This construction forms an outer and inner frame, the inner frame suspended within the outer frame by spring connections and links H. The said link connections can be either a rod provided 45 with suitable eyes to connect with screw-eyes secured in the strips B and G or a coil-spring of suitable strength to support the weight of the bunch of bananas.

J indicates a sack of any soft material, the 50 lower end K tapered to receive the small end of the bunch of bananas. The said sack is secured to the strips G in any suitable and efficient manner. The object of the connecting-springs F is for the purpose of forming a 55 spring-cushion for the inner frame when the same is placed in a horizontal position, preventing the danger of bruising bananas when in transit.

Having fully described my invention, what 60 I claim as new, and desire to secure by Letters Patent, is—

In a banana-case, the combination of the outer skeleton case composed of the series of vertical strips, the hoops surrounding and 65 holding said strips, the inner case composed of a series of vertical strips, the links connecting the strips of the inner to the strips of the outer case, the springs connected to and imposed between the strips of the inner and 70 outer case forming cushions, and the banana-holding sack arranged in and secured to the inner case.

In testimony whereof I affix my signature in presence of two witnesses.

JAMES JACKSON.
